(No Model.)

F. BAUER.

AUTOMATIC SELF ARRESTER ICE CAN FILLER.

No. 501,398.

Patented July 11, 1893.

spring valve tube section 45, the tubular trip head 59, the lateral integral tube 80, the spring valve 58, the plunger piston 56 provided with the lock slot 68, the trip trigger 69, the spring 5 abutting boss 96 on said trigger, the spiral spring 70, the pendent arm 104, the bell crank lever 100 pivoted on said arm, and the pivotal connection of said bell crank lever to said trip rod, that commands the same in the 10 trip action of said trigger; substantially as described.

5. In an automatic self arrester ice can filler, the combination of the water filler tube, the basement tubular shoe 4, provided with the 15 vent holes 10, the washer disk 6 provided with the perforate center 8, the foot valve 11 having the bucket 12, the piston rod 13, the spiral spring 15, the surmounting tube sections 45 and 59, 80, the plunger piston 56 20 provided with the lock slot 68, the automatic spring valve on said piston, the trip trigger 69, the bell-crank lever 100, the trip rod 41 and the globe float 30 arranged to effect the 25 trip and arrest the water flow; substantially as described.

6. In an automatic self arrester ice can filler, the combination of the tube sections 1, 45, and 59, the integral lateral tube 80, the basement tubular shoe 4, the spring valve in said 30 tubular shoe, the piston that carries said valve, the trip foot 14 at the base of said piston and valve, the spring clamp holder 19,

the set-screw 20, the swinging bail 31, the globe float 30 on said bail, the slotted lug on said bail, the trip rod 41, the water supply 35 pipe section 52, the screw-joint nozzle 53, the elastic hose 54, the valve cushion bed 48, the valve 58, the piston 56, provided with the lock slot 68, the spiral spring 64, the stuffing box 71, the gasket 75, the trip trigger 69, the 40 spring abutting boss 96, the spiral spring 70, the screw tube stopper 82, the stuffing box 85, the gasket 88, the screw set tube boss 93, the pendent arm 104, the bell-crank lever pivoted to said arm, having the bail forks 98 that clutch 45 said screw set tube boss on said trip trigger, the eyelet lug 112 in which said trip rod reciprocates, and the pivoted connection of said trip rod to the bifurcated operative end of said bell crank lever; substantially as described. 50

7. The combination of the water filler tube 1, the major spring valve chamber section 45, the tubular trip-head 59, the said spring valve chamber and said tubular trip-head 55 provided with the tubular, elongated piston bed 115, and with the horizontal circumferential grooves 114, around the working course of said piston, and the horizontal water ring packing 116; substantially as described.

FERDINAND BAUER.
